UNITED STATES PATENT OFFICE.

ALBERT CHARLES DAVIS, OF LIVERPOOL, ENGLAND.

ICE-MANUFACTURING APPARATUS.

Application filed December 27, 1919. Serial No. 347,858.

To all whom it may concern:

Be it known that I, ALBERT CHARLES DAVIS a subject of the King of England, residing at 20 Morningside Road, Bootle, 5 Liverpool, in the county of Lancaster, England, have invented certain new and useful Improvements in Ice-Manufacturing Apparatus (for which I have filed an application in England, complete specification accepted 10 Dec. 18, 1919, Patent No. 136,299), of which the following is a specification.

In the manufacture of ice by the direct expansion system wherein water is frozen in compartments or cells, a tank is divided 15 into compartments or cells by a series of parallel hollow partitions. In these hollow partitions a refrigeroric agent, as brine or ammonia is circulated, causing the water to freeze in the form of a plate or block. To release such frozen plates or blocks from the compartment or cell walls is the purpose of this invention and I attain such release without the use of hot gases and without diminution of freezing in the compartments or 20 cells adjacent to those in which the thawing is occurring for the release of the ice.

Briefly described, I provide a circulating system for the refrigerant so that the refrigerant may be first expanded in the hollow 25 partitions of the tank for freezing purposes, and then circulated, without expansion, for thawing purposes. The circulation causes the refrigerant to be cooled for further use.

My invention will now be described by aid of the accompanying drawings, wherein

Figure 1 is a diagrammatic view of a portion of a refrigeratory apparatus embodying features of my invention, and

Fig. 2 is a continuation of the apparatus 40 illustrated in Fig. 1, and for the purpose of understanding this invention the two sheets can be placed side by side so as to make one complete view.

As illustrating the most essential parts of a refrigeratory apparatus, I show a compressor J, a condenser —k—, a receiver —l—, and compartment or cell walls of a tank —d—. The compressor is connected to the condenser in the usual manner and extending from the receiver —l— along the walls —d— are refrigerant inlet pipes 1 and 2, the pipe 1 being connected to the pipe 2 by a branch pipe —a— with valves A and D adjacent the branch pipe —a—, so that 50 these valves may be adjusted to direct the refrigerant into the pipe 1 or into the pipe 2.

The inlet pipe 1 communicates with expansion valves C and these valves communicate with headers or manifolds —b— having a plurality of branch pipes —c— leading 60 to the walls of the tanks —d—. These same walls have discharge or return pipes —g— communicating with suction headers or manifolds —f—, which in turn are adapted 65 to communicate, through valves F, with a discharge pipe 3 extending along the tanks —d— and connected to the compressor —J—. The refrigerant can be circulated for freezing purposes until the ice on the 70 walls or plates has reached a required thickness, and in order that the circulation may be reversed for thawing purposes other connections are provided.

The inlet pipe 2 is connected by pipes —h— to the suction headers —f— and on 75 said pipes are valves —E—, which during the freezing circulation are closed, but are adapted to be opened, together with the valve —D— to permit of the refrigerant entering the suction heads —f—, pipes 80 —g—, pipes —c—, headers or manifolds —b— and from these headers through valves B and by-path pipes —e— to the inlet pipe 1. The valves B and the pipes 85 —e— will establish communication between the inlet pipe 1 and the headers —b— when the expansion valves —C— are closed.

In addition to the by-paths —e— and valves —B—, I may provide by-paths —i— and expansion valves —G— between the 90 headers or manifolds —f— and the discharge pipe 3. By opening the expansion valves —G— any liquid remaining in the tank walls or plates can vaporize slowly into the discharge pipe 3 without disturbing the 95 tank or tanks already in the process of freezing. The valves —G— are permitted to remain open until the whole of the liquid refrigerant has vaporized from the walls or plates which have been thawed, after which 100 the valves —G— are closed and the tank or tanks again opened to freezing. In some instances it may not be necessary to use the by-paths —i— and expansion valves —G— and if omitted the liquid refrigerant passes 105 gradually through the valves —F— to the discharge pipe 3 after the ice is harvested.

The admission of refrigerant to the inlet pipes 1 and 2 may be effected and controlled 110 in any other convenient manner, and obviously, if desired, inlet pipe 1 may be connected to the headers —f— instead of

the headers —*b*—, and inlet pipe 2 may be connected with the headers —*b*— instead of the headers —*f*—.

The refrigerator apparatus may be either 6 operated for freezing or thawing purposes, and to place the apparatus in condition for freezing, the following adjustments are made. Valves A, C, and F are opened and 10 valves D, E, B and G are closed. The refrigerant passes from the condenser through pipe 2 to the branch —*a*—, through valve A, pipe 1 and valve C to header —*b*—. From this header the refrigerant passes through pipes C to the several tank walls or plates 15 and returns by pipes —*g*— to the suction header —*f*— from where it passes through the open valve F to the suction line pipe 3 of the apparatus.

When the ice on the walls has reached the 20 required thickness the valves C and F are closed, to isolate the tank, and to release or thaw off the ice from the tank walls or plates, the following adjustments are made.

Valves D, E and B are opened, and valves 25 A, G, C and F are closed. In consequence of this valve adjustment the direction of flow is reversed, the refrigerant returned as a liquid to pipe 1 through which other tanks in the process of freezing are supplied.

What I claim is:—
1. In ice-manufacturing apparatus of the direct-expansion type, and wherein the apparatus includes ice-freezing walls, means 35 for delivering liquid refrigerant to the freezing walls under refrigerant-evaporation conditions to produce the freezing, and means for delivering the refrigerant to said walls while maintaining the refrigerant under pressure sufficient to prevent material

evaporation of the refrigerant, whereby thawing conditions are produced for removal of the formed ice from such walls.

2. Apparatus as in claim 1 characterized by a flow-path for the refrigerant leading 45 from either of two lines of refrigerant supply each having controllable connection with the main source of supply, a suction line, and means operatively connecting the suction line to such flow-path when one of 50 said supply lines is active to produce the freezing, said means being operative to disconnect the suction line from such flow-path when the other of said supply lines is active within the flow-path.

3. Apparatus as in claim 1 characterized in that the apparatus includes a plurality of freezing units, and characterized by a flow-path for the refrigerant leading from either of two lines of refrigerant supply, 60 each line having controllable connection with the main source of supply, a suction line, means operatively connecting the suction line to such flow-path when one of said supply lines is active to produce the freezing, said means being operative to disconnect the suction line from such flow-path when the other of said supply lines is active within the flow-path, the control connections of the flow-path being such that 65 when the suction line of a unit is inactive such connections are operative to render the first of said supply lines active beyond the freezing walls to receive the refrigerant from such walls and deliver it as the refrigerant 70 supply for the freezing activity of the freezing walls of a succeeding freezing unit.

In testimony whereof I affix my signature.

ALBERT CHARLES DAVIS.
